DESIGN FOR A UNIFORM

Mary Estel Donahue, St. Louis, Mo., assignor to Angelica Jacket Company, St. Louis, Mo., a corporation of Missouri

Application July 20, 1940, Serial No. 93,810

Term of patent 7 years

To all whom it may concern:

Be it known that I, Mary Estel Donahue, a citizen of the United States, residing at the city of St. Louis, State of Missouri, have invented a new, original, and ornamental Design for a Uniform, of which the following is a specification, reference being made to the accompanying drawing, forming a part thereof, in which Figure 1 is a front elevational view and Figure 2 is a rear elevational view of a uniform embodying my new design.

I claim:

The ornamental design for a uniform, substantially as shown.

MARY ESTEL DONAHUE.
